UNITED STATES PATENT OFFICE.

JAMES G. BROOKS, OF RUSHVILLE, NEBRASKA.

HINGE OR HANGER.

1,352,782.

Specification of Letters Patent. Patented Sept. 14, 1920.

Application filed June 4, 1920. Serial No. 386,445.

To all whom it may concern:

Be it known that I, JAMES G. BROOKS, a citizen of the United States, residing at Rushville, in the county of Sheridan and State of Nebraska, have invented certain new and useful Improvements in Hinges or Hangers; and I do hereby declare the following to be a full, clear, and exact description of the invention, such as will enable others skilled in the art to which it appertains to make and use the same.

This invention relates to devices for hanging or mounting storm windows and doors, screens, and the like, in the casings or frames thereof, and has for its primary object the provision of novel and improved, yet simple and inexpensive means for detachably hanging or mounting the door, window, screen or other barrier within its frame or casing and enabling the barrier to be readily applied and removed.

Another object is the provision of such a device enabling the barrier to be fastened and unfastened from the side opposite to the fastening means or hinge connection, such as for the purpose of enabling the door, window, screen or other barrier to be mounted in the frame or casing and fastened and unfastened from the inside, with the fastening means or hinge connection on the exterior.

A still further object is the provision of means carried by the barrier member and operable manually from one side of the barrier member and having means on the opposite side movable into and out of engagement with keepers on the frame or casing, thereby affording convenient means for mounting the barrier member, with provision for the quick and convenient application of the barrier to and the removal or demounting thereof from the frame or casing.

With the foregoing and other object in view, which will be apparent as the description proceeds, the invention resides in the construction and arrangement of parts hereinafter described and claimed, it being un-

derstood that changes can be made within the scope of what is claimed without departing from the spirit of the invention.

The invention is illustrated in the accompanying drawing, wherein:

Figure 1 is an elevation showing a pair of the hinges or hangers supporting the barrier in closed position.

Fig. 2 is a similar view showing the barrier swung open.

Fig. 3 is a section on the line 3—3 of Fig. 1.

The present improvements are useful for hinging or hanging a storm window or door, screen, or other barrier within the casing or frame thereof, and the part 7 can be taken to represent any such barrier to be demountably hinged or hung within its frame or casing 8.

Keepers or hinge members are carried by the frame 8, and comprise shanks 9 which are shown as being pointed, so as to be driven into the frame on the outer side thereof, and the outer terminals of the shanks are bent into hooks 10, the ends of which are also driven slightly into the frame 8 to retain the keepers in proper position. As shown, the hooks 10 are in slightly inclined 75 positions, with one hook inclined reversely to the other.

Catches or hinge members are carried by the barrier 7 adjacent to the vertical edge thereof nearest the keepers, and these catches 80 comprise the journal portions 11 extending transversely of the barrier from one side thereof to the other, with hanger arms 12 extending at an angle from the outer ends of said journal portions. These arms 12 85 have hooks 13 to swing in a plane parallel with the barrier into the hooks 10 of the keepers, thereby not only hanging the barrier from the frame, but also providing a hinge connection which permits the barrier 90 to swing open, as shown in Fig. 2. The bearings for the journal portions 11 constitute, as shown, doubled strips 14 secured to the vertical edge of the barrier, and having offset or separated portions 15 providing 95 bearings in which the journal portions 11 are

mounted for rotation. As shown, one terminal of each strip 14 is extended beyond the other and is bent at an angle to overlap the corresponding horizontal edge of the 5 barrier whereby to serve as a corner piece for protecting and reinforcing the corner of the barrier, and making the structure more rigid.

Operating arms 17 extend at an angle 10 from the inner ends of the journal portions 11 in a direction opposite to the direction in which the arms 12 extend, and said arms 17 have finger pieces 18 extending at an angle from the free ends thereof away from 15 the barrier at the inner side thereof. Each catch or hinge member is bent of a single length of wire or other suitable material, as shown, and constitutes a lever having the journal or fulcrum portion 11 journaled 20 through the barrier from one side to the other, with the short arm 12 on the outside and having a hook 13 or means to engage the keeper, and the long arm 17 on the inside and having a finger piece or handle for 25 swinging the hook 13 into and out of engagement with the keeper. It is preferable to provide studs 19 on the inner surface of the barrier over which the arms 17 can snap when said arms are swung to move the 30 hooks 13 through the keepers, thereby preventing accidental disconnection. These studs may be headed tacks driven into the barrier, or the like, in the proper position so that the arms 17 swing over said studs or 35 heads of the tacks when the hooks 13 are swung into position in engagement with the keepers, as seen in Fig. 1. One of the hooks 13 is shown in Fig. 1 in dotted lines in releasing position, and the hooks swing 40 in opposite directions into the keepers in the arrangement shown.

The barrier can be easily mounted in the frame from the inside. Thus, after the barrier is passed through the door or window opening from the inside, and moved into position within the frame, with the catches or levers swung to move the hooks 13 to releasing position, as indicated in dotted lines in Fig. 1, it is then an easy 45 matter to swing said catches or levers by the aid of the finger pieces 18, to move the hooks 13 through the hooks 10 of the keepers. Thus, when the arms 17 are swung on the 50 inside of the barrier, this moves the hooks 13 on the outside through the keepers, and the arms 17 are then retained in position by studs 19 or other equivalent means. The barrier is then free to swing open due to the 55 hinge connection between the hooks 13 of the catches and the hooks 10 of the keepers, although the devices can be used at the opposite vertical edges of the barrier and frame if desired. The barrier is readily removed,

by swinging the arms 17 from the inside of the barrier, to withdraw the hooks 13 from the keepers, thereby releasing the barrier so that it can be readily taken in through the opening.

By the provision of the hooks or hinge portions 10 of the keepers being inclined, 70 they can be so arranged as to facilitate the movement of the hooks 13 therethrough when the barrier is in closed position, and to impede or prevent the withdrawal of the hooks therefrom when the barrier is in open 75 position, as seen in Fig. 2. In other words, the inclination of the hooks or hinge portions 10 is such as to enable the hooks 13 to move freely into same with the barrier in closed position, and making the removal of 80 the hooks 13 from the keepers difficult if not impossible when the barrier is in open position, due to the reversal of the positions of the hooks with respect to the keepers as seen in Fig. 2. This will prevent the barrier 85 being taken down from the outside, without considerable difficulty, if at all, although the barrier can be readily secured and released from the inside when in closed position.

The keepers and catches can be readily 90 and cheaply manufactured from wire or other stock, and the bearing members also cheaply made, in order that the devices can be supplied at small cost, although they can be made more elaborate within the scope of 95 the appended claims to suit other needs or circumstances, without departing from the principles involved.

Having thus described the invention, what 100 is claimed as new is:—

1. A hinge comprising a hinge member to be carried by one side of a frame, and a hinge member having means for mounting it on a barrier for movement in a plane parallel with the barrier, and provided with means on one side for detachably engaging the first named hinge member and means on the opposite side for manual operation to move said means into and out of engagement with the first named hinge member.

2. A hinge comprising a hinge member to be carried by one side of a frame, and a hinge member to be carried by a barrier having a journal portion to extend from one side of the barrier to the other, and arms extending from said journal portion at the opposite sides of the barrier, and one arm having means to detachably engage the first named member, and the other arm being manually operable for moving the first named arm to engage and disengage the first named hinge member.

3. In a hinge construction, the combination with a frame and a barrier, of hinge members carried by the frame, and pivoted hinge members carried by the barrier, the

hinge members having loops and hooks movable into and out of engagement in one position of the barrier and so arranged as to prevent disengagement in the other position of the barrier.

4. In a hinge construction, the combination with a frame and a barrier, of hinge members carried by the frame having loops, and pivoted hinge members carried by the barrier having hooks to move through said loops, said loops being arranged for the entrance and withdrawal of the hooks when

the barrier is in one position and to prevent the removal of the hooks when the barrier is in the opposite position.

15

In testimony whereof I have signed my name to this specification in the presence of two subscribing witnesses.
